UNITED STATES PATENT OFFICE.

ARVINE N. THOMAS, OF CANTON, OHIO.

GAME APPARATUS.

No. 889,066.

Specification of Letters Patent.

Patented May 26, 1908.

Application filed May 1, 1907. Serial No. 371,349.

To all whom it may concern:

Be it known that I, ARVINE N. THOMAS, a citizen of the United States, and resident of Canton and State of Ohio, have invented 5 certain new and useful Improvements in Game Apparatus, of which the following is a specification.

The present invention has relation to game apparatus and has for its object to provide 10 an apparatus for practically reproducing in a game apparatus the game of base ball and it consists in the parts and arrangement and combination of parts hereinafter described, and particularly pointed out in the claims.

15 In the accompanying drawings, forming part of this specification:—Figure 1 is a top view. Fig. 2 is a transverse section on line A—B. Fig. 3 is a transverse section on line C—D. Fig. 4 is a bottom or underside view 20 of the base. Fig. 5 is a perspective view of the field plate removed, showing the center plate removed, also showing the base plate removed. Fig. 6 is a top view of the center plate. Fig. 7 is a detached view of the bat 25 operating lever and its actuating spring. Fig. 8 is a view of one of the base levers and its spring. Fig. 9 is a view showing one of the corner base pockets of the frame. Fig. 10 is a detached view of the pitcher's guide. 30 Fig. 11 is a bottom or underside view of one corner of the base. Fig. 12 is a detached view of one of the image players.

Similar numerals of reference indicate corresponding parts in all the figures of the 35 drawing.

In the accompanying drawings, 1 represents the base plate, which is formed of any desired size and its border or edge provided with the gutter 2. To the base 1 is connected 40 the field plate 3 having a central diamond-shaped opening, which field plate is spaced from the top or upper side of the base 1 as illustrated in Figs. 2 and 3. To the base plate is attached the center plate 4, said 45 plate being formed of such a size that when placed in proper position its edges will be located a short distance from the edges of the opening formed in the field plate by which arrangement the slots or ways 5 are produced, said slots or ways being located and 50 arranged as illustrated in Fig. 1 and as shown they form a center or diamond. To the center plate 4 is attached the pitcher's guide 6, said guide being connected to the bottom 55 or underside of the center plate 4 and extended upward and forward of the aperture

7, said guide being provided with the aperture 8, which aperture is for the purpose of dropping the ball into the batter's groove 9. At the lower or outer end of the batter's groove 9 is located the bat 10, which bat is pivotally attached to the center plate 4 and the base plate 1. The bat actuating lever 11 is pivotally connected between its ends, and its outer end extended far enough to be actuated by one of the players. The lever 11 is provided with the slot 12, through which slot the crank portion 13 of the bat 10 is passed. It will be understood that by moving the lever upon its pivotal point the bat 10 will be brought into the path of the ball, dropped by the pitcher through the aperture 8 and for the purpose of providing a bat action when the lever 11 is released the spring 14 is provided, which spring engages 60 the lever 11, said spring being connected at its opposite end to the post 15, which post is secured in fixed position in any convenient and well known manner.

The field plate 3 is provided with the short stop, right, center and left field apertures 16, back of which are located the hoods 17, the short stop, left, center and right field apertures are located in the depressions 18 65 19, 20, and 21 under which are located the grooves 22, 23, 24 and 25, which grooves are formed in the base 1 and are for the purpose of receiving and guiding the balls to the gutter 2 when they have passed through the apertures 16. At the 1st, 2nd and 3rd base 70 positions are located the brackets 26, which brackets are secured to the top of the base plate 1 substantially as shown in Fig. 4, and are provided with the apertures 27, which apertures are normally closed by the base 75 levers or pivoted bars 28, said pivoted bars being mounted upon the posts 29, said posts being secured to the field plate 3.

For the purpose of normally holding the base levers or bars 28 in position to close the 80 apertures 27, the springs 30 are provided which springs are connected to the posts 29 and are arranged for engagement with the base levers 28. Directly above the apertures 27 are located the openings 31; back 85 of which openings are located the hoods 32, which openings communicate with the slots or ways 5 as best illustrated in Fig. 1. The various hoods 17 and 32 are for the purpose of catching the ball in the event the ball is 90 batted so as to find its way directly to the various bases, short stop, left, right and cen- 95 100 105 110

ter field and the base levers 28 are for the purpose of permitting the ball to drop through the base apertures when brought into position to open the apertures.

5 It will be understood that by providing the various hoods that a fly catch is possible, when the ball passes directly from the bat into any one of the openings located in front of the hoods at 1st, 2nd and 3rd bases, short 10 stop, left, center and right fields. Directly back of the catch out aperture 7 is located the vertical portion 33 of the pitcher's guide 6, by which arrangement the ball is liable to strike said vertical portion which is extended above the center plate 4 and the 15 horizontal portion of the pitcher's guide is spaced a sufficient distance from the upper face of the center plate 4 to allow the ball to pass under the horizontal portion when 20 struck from the bat and find its way through the catch out aperture 7 and pass to the gutter by way of the groove 24. If the batter misses the ball as it passes down the groove 9 it will find its way through the aperture 34 25 and be conveyed to the gutter by means of the groove 35. When a run is made an image player 36 is placed in the position to be moved along in the proper slot 5 and the image moved from base to base according 30 to the rules of a base ball game.

For the purpose of holding the images 36 in an upright position they are mounted upon the bases 37 which bases are provided with the disks or headed portions 38, said headed 35 portions being of such a size that they can be passed through the home base aperture 34 and through the heart-shaped opening 31. The object and purpose of forming the openings heart-shaped or of similar shape is to 40 prevent a continuous run at the various bases or in other words the images must be turned and backed into the recesses 40 in order to bring the base 37 into alinement so as to be continued through the slot 5. The 45 field plate 3 is bounded upon its sides with the fence 41 which fence is formed by bending a portion of the metal at substantially right angles to the field plate 3.

For the purpose of providing means for 50 making a home run the rear fence is provided with the apertures 42, through which apertures it is possible but not easy to knock the ball and in order to increase the difficulty of sending the ball through the home run apertures 42, these apertures are located at the 55 ends of the semi-circular ridge 43.

The base 1 has reinforced contact surfaces 44 (see Fig. 2) which are apertured to receive bolts 45 connecting said base and the 60 plate 3, the level of the latter being maintained by coextensive spacing sleeves 45^a surrounding the bolts between the base 1 and the plate 3.

For the purpose of preventing the base 65 plate 1 from marring the furniture on which

the apparatus is supported and at the same time preventing the game apparatus from sliding or slipping the cushioned knobs 46 are provided, which are attached in the usual manner.

70 For the purpose of holding the center plate 4 in position, suitable bars or screws 47 are provided. The slots or ways 5 are arranged to form or bound a diamond and at their junctions are located the 1st, 2nd, 3rd bases 75 31 and home base aperture 34.

For the purpose of presenting a smooth level surface on which to secure the center plate 4 and the edges of the field plate 3, which adjoin the slots 5, the base 1 is formed 80 in such a manner that the surfaces 48 which support the plate 4, and 49 which support the plate 3 are in a common plane and the surfaces 50, 51, 52 and 53 slope downward from the surfaces 49 toward the gutter 2.

85 It will be observed that since the surfaces 48 and 49 are on a level the edges of the field plate 3 and the center plate 4 which form the slots 5 will be perfectly level and opposite in relation to each other when assembled together as shown in Fig. 1.

For the purpose of providing a channel in which to allow the base part 38 of the image players 36 to pass through the slots 5 from base to base the recesses 54 are formed in the 95 base plate 1. These recesses 54 are provided with the sunken portions 55 at their 1st, 2nd and 3rd base ends for the purpose of bringing the bottom portion of the recesses 54 on a level with the top surface of the brackets 26 100 when said brackets are secured in position as shown in Fig. 4.

For the purpose of providing a stop against which the levers 28 are held in position by the springs 30 the lips 56 are formed upon the brackets 26 as shown in Fig. 9 said lips being located at such a point that the levers will be stopped in the proper position to close the apertures in the brackets.

Having fully described my invention, what 110 I claim as new and desire to secure by Letters Patent, is—

1. A game apparatus comprising a base, a field-plate located above the base, said field-plate being provided with base openings and with a diamond-shaped central opening, a diamond-shaped center plate disposed conformably in the central opening and spaced from the edges thereof, said field plate being provided with short stop, right, 115 left and center field apertures, hoods located back of said apertures, a pitcher's guide, said center plate being provided with a groove leading from the pitcher's guide toward the home base opening in the field-plate, and 120 bat mechanism located in the groove, substantially as and for the purpose specified.

125 2. A game apparatus comprising a base, a field-plate located above the base, said field-plate being provided with base openings and 130

with a diamond-shaped central opening, a diamond-shaped center plate disposed conformably in the central opening and spaced from the edges thereof, said field-plate being provided with short stop, right, left and center field apertures, hoods located back of the apertures, a pitcher's guide, said center plate provided with a groove leading from the pitcher's guide toward the home base opening of the field plate, bat mechanism located in the groove, and image players adapted to move around the center field-plate, substantially as and for the purpose specified.

3. A game apparatus comprising a base, a field-plate located above the base, said field-plate being provided with base openings and with a diamond-shaped central opening, a center plate disposed conformably in the central opening and spaced from the edges thereof, said field-plate provided with short stop, right, left and center field apertures, hoods located back of the apertures, a pitcher's guide said center plate being provided with a groove leading from the pitcher's guide toward the home base, and bat mechanism located in the groove and image players adapted to move in the space between the center and field-plates said field plate being provided with apertures located at the corners of the central openings, substantially as and for the purpose specified.

4. In a game apparatus, the combination of a base-board provided with grooves and a gutter, a field-plate provided with apertures, hoods located back of the apertures, a center plate provided with an inclined groove, bat mechanism located in the path of the groove, a pitcher's guide secured to the center plate, said center-plate being provided with a catch-out aperture below the pitcher's guide, said field-plate being provided with base apertures at the corners of its central opening, substantially as and for the purpose specified.

45 5. In a game apparatus, the combination of a base provided with gutters, and formed with grooves in its upper surface and communicating with the gutters, a center-plate supported upon the base, said center-plate being provided with a pitcher's guide and with a groove leading therefrom, a field-plate surrounding the center-plate and having its adjacent inner edges spaced therefrom, bat mechanism located in the groove leading from the pitcher's guide, said field plate being provided with base apertures, means for closing the base apertures, the spaces between the mutually adjacent edges of the field and center-plates affording ways arranged in the form of a diamond and communicating with the base apertures, said field plate being also formed with right, left and center field apertures and a short stop aperture, hoods located back of said apertures and image players adapted to move in

the ways, substantially as and for the purpose specified.

6. In a game apparatus, the combination of a base, a field plate supported thereon said field-plate being provided with a flange or fence, and with short stop, right, left and center field depressions, elevations separating said depressions said field plate being provided with home run apertures located back of and in substantial alinement with the elevations located around the center field portion of the plate, a center plate located centrally thereof, said center plate being formed with a pitcher's guide a groove leading from the pitcher's guide, bat mechanism located in said groove, said base being formed with ball receiving grooves in its upper face.

7. In a game apparatus, the combination of a base, a field plate supported thereon, said field plate being provided with a semi-circular ridge, a flange or fence, and with home run apertures located at the ends of the semi-circular ridge, said semi-circular ridge being located in front of the center field, said plate having short stop, right, left and center field apertures formed therein, a center plate, a pitcher's guide located centrally of the center-plate, said center-plate being formed with a groove leading from the pitcher's guide, and bat mechanism located in said groove, said base having ball receiving grooves formed or in its upper face, substantially as and for the purpose specified.

8. In a game apparatus, the combination of a base, a field-plate supported thereon, said field-plate being provided with a semi-circular ridge, a flange or fence, and with home run apertures located at the ends of the semi-circular ridge, said semi-circular ridge being located in front of the center field portion of the plate, said plate having short stop, right, left, and center field apertures formed therein, a center plate, a pitcher's guide located centrally thereof, said center plate being formed with a groove leading from the pitcher's guide, bat mechanism located in said groove, said base having ball receiving grooves formed in its upper face, said field plate being formed with base apertures and means for normally closing said apertures, substantially as and for the purpose specified.

9. In a game apparatus, the combination of a base, plates supported above the base, one of said plates surrounding the other, the mutually adjacent edges of the plates being spaced to afford ways arranged in the form of a diamond, a pitcher's guide located centrally of the inner plate, said inner plate being formed with a groove leading from said guide, bat mechanism located in the groove said inner plate being formed with a catch out aperture located at the rear of the pitcher's guide, and image players adapted

- to move in the ways, one of the plates being formed with base apertures located at the junction of the ways, substantially as and for the purpose specified.
- 5 10. In a game apparatus, the combination of a base, plates supported above the base, one of said plates surrounding the other, the mutually adjacent edges of the plates being spaced to afford ways arranged in the form 10 of a diamond, a pitcher's guide located centrally of the inner-plate, said inner-plate being formed with a groove leading from said guide, bat mechanism located in the groove said inner plate being formed with a catch 15 out aperture located at the rear of the pitcher's guide, image players adapted to move in the ways, one of the plates being formed with base apertures located at the junctions of the ways, and hoods located at the rear

of the 1st, 2nd and 3rd base apertures, substantially as and for the purpose specified. 20

11. In a game apparatus, a structure including a supporting base, spaced plates arranged thereabove one within the other, the inner plate having a centrally located pitcher's guide and a groove leading therefrom, one of the plates being formed with base apertures communicating with the spaces between the plates, and bat mechanism located in the groove. 25

In testimony that I claim the above, I have hereunto subscribed my name in the presence of two witnesses. 30
